UNITED STATES PATENT OFFICE.

JOHN B. WATLING, OF CHICAGO, ILLINOIS.

AMUSEMENT APPARATUS.

Application filed May 26, 1923. Serial No. 641,607.

This invention relates to amusement apparatus of the coin-controlled type but more particularly to fortune-telling devices in which the operator may select any one of a number of available questions and the mechanism will display an answer to the question selected.

The primary object of the present invention is to provide a novel and ingenious device of the type described which is simple in construction and capable of withstanding hard use.

The particular embodiment of my invention which I have chosen to illustrate the principles thereof is incorporated in a weighing scale of well-known type and the mechanism is so constructed and arranged that a single coin will cause the apparatus to register the weight of the operator and the answer to his question.

The many other objects and advantages of my invention will be better understood by reference to the following specification when considered in connection with the accompanying drawings, in which—

Fig. 1 is a front elevation of a portion of the apparatus.

Fig. 2 is a rear elevation of the apparatus with wall of casing removed, showing for-
tune-telling mechanism, and

Fig. 3 is a detail view.

Referring to the drawings, the apparatus is substantially enclosed in a casing 10 provided with an arcuate opening or window 11 to expose the weighing scale dial 12. The coin slot is located at 13. A window 14 exposes a segment of the revolute question dial 15. A similar window 16 exposes a segment of the revolute answer dial 17. An operating knob 18 is connected to the outer end of a shaft 19 connected to the dial 15 and projecting through the front of the casing.

The weighing mechanism is not shown in detail as this mechanism forms no part of the present invention. A coin inserted in the slot 13 actuates a rock arm 20 to release the ratchet wheel 21 controlling this mechanism. One extremity of this rock arm is provided with a coin pocket 9 disposed beneath the lower end of the chute 22 connected to the coin slot. The weight of the coin causes the pocketed end of this arm to swing downwardly and lift the pawl 23 from the ratchet wheel. The continued downward movement of this arm permits

the coin to drop from the pocket into the coin chute 24.

At the bottom of the chute 24 is a second coin pocket 25 on the extremity of a rock arm 26, pivotally mounted on the supporting frame 27 at 28. This arm 26 is normally held with the pocket 25 in the position indicated in solid lines in Fig. 2 by the spring 29. A stop 30 projects laterally from this arm and is normally in position to engage a catch 31 on the inner end of the lever 32. This catch is pivotally connected to the lever at 33 and its inner end 34 is bent laterally to overlie the lever. A spring 35 normally holds this end against the lever as indicated. The catch 31 prevents the lever from swinging downwardly when the stop 30 is in position (Fig. 3). Rocking of the arm 26 in the manner described releases the stop from the catch 31. As soon as a coin has been emptied from the pocket 25 into the coin box 36, the spring 29 causes the arm to return to normal position. The upward movement of the lever 32 past the stop 30 is permitted by the rocking of the catch 31 upon its pivot.

The lever 32 is pivotally connected to the frame 27 at 40 and a second lever 41 is connected to the inner end of the lever 32 to form therewith substantially a bell crank. The outer extremity 42 of this lever 41 is bent laterally and carries at its outer end a shutter 43 to normally close the window 16 and conceal the answer dial. A guide 44 is provided for the lever 41.

The answer dial 17 is mounted on the revolute shaft 50 supported by the frame 27. A sprocket wheel 51 is likewise secured on this shaft and a drive chain 52 operatively connects this sprocket with a sprocket 53 secured on the shaft 19 carrying the operating knob 18.

A short lever 54 is pivotally mounted on the frame at 55. One end of this lever 54 is provided with a roller 49 which operates upon the periphery of the sprocket 51 and is held in yielding engagement therewith by the spring 56. The sprocket acts as a cam and the roller as a cam follower so that rotation of the sprocket causes a rocking motion to the lever 54. An arm 57 is secured at its upper extremity to the lever 54 and its lower extremity is connected to the lever 41 by a link 58. The forcing of the roller 49 outwardly by a tooth of the sprocket 51 causes the lever 41 to swing in a clockwise

direction and to move the shutter to closed position. The catch 31 permits the outer end of the lever 32 to swing past the stop 30 but prevents the dropping of the lever 5 past this stop when the roller 49 enters the next depression between the teeth on the sprocket 51. When the stop 30 is withdrawn from the catch 31 by the downward movement of the arm 26 in the manner described, 10 the lever 41 swings in a counterclockwise direction by force of gravity and moves the shutter 43 to bring the opening 60 in this shutter into registration with the opening 16 in the casing, exposing the particular 15 answer to the question. This counterclockwise movement of the lever 41 is permitted by the slot 61 in the link 58 and the extent of such movement is determined by an adjustable stop 62 secured on the frame 27. 20 The lever 41 is shown in solid lines (Fig. 2) in closed shutter position, and in open shutter position in dot. The slot 61 in the link 58 also permits the movement of the arm 57 caused by the continuous rotation of the 25 shaft 19 without materially moving the lever 41 when this lever has been brought to closed shutter position.

In the present embodiment of the invention there are thirty-two teeth on the sprocket 51 connected to the answer dial and eight teeth on the sprocket 53. Therefore, the dial 15 makes four revolutions to each revolution of the answer dial 17. There is one question on the dial 15 for each tooth or 30 eight questions, and in the same manner thirty-two answers on the dial 17. It will thus be obvious that four answers are provided for each question and they are so arranged on the dial 17.

40 In the operation of the device, the operator rotates the knob to the right until the question is exposed which he desires to ask.

The chain and sprocket connection has brought one of the four possible answers to this question in position at the window 16 45 but this answer is concealed by the shutter 43. He now drops his coin in the slot 13 and the descending coin in turn renders the weighing apparatus operative and causes the shutter to be moved to open position, 50 exposing the answer. The pointer 70 of the weighing apparatus indicates the weight on the dial 12 in the usual manner.

It will be readily evident that this device is amusing and offers an inducement to the 55 public to use the weighing scale. The construction is simple and strong and fully capable of withstanding the hard usage to which such a device is subjected.

I am aware that many changes may be 60 made in the construction and arrangement of parts without departing from the spirit of my invention, and I reserve the right to make all such as fairly fall within the scope of the following claim.

65 I claim as my invention:

In apparatus of the class described, the combination of a casing provided with a plurality of windows therein, a revoluble dial in said casing having a series of questions thereon adapted to be successively brought into position before one of said windows and a series of answers thereon adapted to be successively brought into position before another of said windows, means 70 for revolving said dial, the questions and the answers being arranged in independent rings, a shutter adapted to normally conceal the answer in said position, and means for shifting said shutter to expose said answer, 75 said means being released by the insertion of a weight to permit shifting of the shutter by gravity.

80 JOHN B. WATLING.
